DESIGN FOR A BATHTUB

Harlow N. Davock, Birmingham, Mich.

Application April 1, 1935, Serial No. 56,166

Term of patent 14 years

To all whom it may concern:

Be it known that I, Harlow N. Davock, a citizen of the United States, residing at Birmingham, in the county of Oakland and State of Michigan, have invented a certain new, original, and ornamental Design for Bathtubs, of which the following is a specification, reference being had to the accompanying drawing, forming a part thereof, and in which—

I claim:

The ornamental design for a bathtub as shown.

HARLOW N. DAVOCK.
